UNITED STATES PATENT OFFICE.

JOHN R. ROSE AND EDWARD L. CALEY, JR., OF PHILADELPHIA, PA.,
ASSIGNORS TO COX, WHITEMAN & COX, OF SAME PLACE.

DESIGN FOR COOKING-STOVE.

Specification forming part of Design No. 7,450, dated May 19, 1874; application filed May 6, 1874.
[Term of Patent 7 years.]

To all whom it may concern:

Be it known that we, JOHN R. ROSE and EDWARD L. CALEY, Jr., of the city of Philadelphia, in the State of Pennsylvania, have invented a Design for the Plates of Cook-Stove, of which the following is a specification:

The nature of our invention is fully represented in the accompanying engraving, to which reference is made.

A represents the oven-door; B, the ash-box door; C, one of the side plates of the stove; and D, one of the vertical corners of the front and sides. The oven-door A is a flat panel, with four sunken panels, divided by a cross, the said flat panel being raised on rounded edge-moldings, as shown. The ash-box door B is substantially like the oven-door A in its ornamentalations, with the difference that the central ornament of the door B is on a swinging plate, as shown. The side plate of the stove has a slightly-raised panel, with four sunken panels, divided by a cross, as shown. The vertical corners of the front are rounded and plain, and the lower end of the one next to the ash-door B flared outward to meet the sloping draft-slide E, as shown.

What we claim as our invention is the design for the plates of a cook-stove, consisting of the following, viz:

1. The flat panel of the oven-door A, raised on the rounded edge-molding, and the face thereof divided by the ornamented cross into the four small sunken panels, as shown.

2. The flat panel of the ash-box door B, raised on the rounded edge-molding, and the face of said panel divided by the cross into four small sunken panels, and the central ornament of the cross placed on the swinging plate of the said door B, as shown.

3. The slightly-raised panel on the side plate C, the said panel being divided by the plain cross thereof into the four small sunken panels, as shown.

4. The rounded vertical corner D, (between the side plate C and the ash-box door B,) with its lower end flared outward to correspond with the sloping end of the draft-entrance projection E, as shown.

JOHN R. ROSE.

EDWARD L. CALEY, JR.
